(57) **CLAIM**

The ornamental design for a gemstone, as shown and described.

DESCRIPTION

FIG. 1 is a top plan view of a gemstone showing our new design;

FIG. 2 is a bottom plan view of the invention; and,

FIG. 3 is a front side view of my invention, wherein each view taken from the right, left and back sides are identical to the front side view.

1 Claim, 1 Drawing Sheet

FIG. 1

FIG. 2

FIG. 3
